MECHANICAL PENCIL

Edward J. Neary, St. John's, Newfoundland

Application June 20, 1934, Serial No. 731,449

3 Claims. (Cl. 120—17)

The object of the present invention is to provide a mechanical pencil of a type in which the lead may be propelled by reciprocating a sleeve mounted on the exterior of the pencil barrel, and 5 the specific object of the invention is to provide a pencil of such type which will be sure in its action and inexpensively manufactured and which will hold relatively long leads in reserve supply within the barrel of the pencil.

10 Further objects will hereinafter appear.

The invention will be described with reference to the accompanying drawings, in which

Fig. 1 is a plan view of an embodiment of the invention.

15 Fig. 2 is a front end elevation of the same.

Fig. 3 is an enlarged longitudinal section on the line 3—3, Fig. 1, with the propelling sleeve in retracted position.

20 Fig. 4 is a fragmentary longitudinal section showing the propelling sleeve and associated means in forward but not extreme position.

Fig. 5 is a view similar to Fig. 4, showing the propelling sleeve in extreme forward position.

25 Fig. 6 is a fragmentary plan view of the front portion of the pencil barrel.

Fig. 7 is a plan view of the propelling wedges.

Fig. 8 is a plan view of the propelling sleeve.

20 Figs. 9, 10, 11, and 12 are, respectively, transverse sections on the lines 9—9, 10—10, 11—11 and 30 12—12, Fig. 3.

Fig. 13 is a plan view of a modified form of the invention.

Fig. 14 is a front end view of the device of Fig. 13.

35 Fig. 15 is an enlarged longitudinal section of the device shown in Fig. 13, partly broken away.

Fig. 16 is a transverse section on the line 16—16, Fig. 15.

40 Fig. 17 is a plan view, partly broken away, of the pencil barrel of Fig. 15.

Fig. 18 is a plan view of the propelling sleeve of the device shown in Fig. 15.

45 Referring to Figs. 1 to 12 inclusive, I have shown a pencil formed of metal, or the like, and comprising a barrel 1 longitudinally supporting a lead tube 2 for a length of lead indicated at 3. Toward the rear end of the barrel, sleeve 2 is supported by four studs 4 which may be secured to the tube in any suitable way and pass through 50 apertures in barrel 1 and then headed over. The tube may be secured in any other suitable way so as to permit passage of spare leads into barrel space surrounding lead tube 2. In the present instance, the rear end of barrel 1 is formed with 55 an annular shoulder 1x against which may abut

an eraser sleeve 5 having rolled threads 5x for securing and holding of an eraser 6.

Toward its forward end, barrel 1 is reduced in diameter and the reduced forward end receives the plug-like rear end 7 of a tip member having 5 two heads 8 and spaced guide bars 8x. Plug 7 is apertured to receive the lead 3 which thence passes between the guide bars 8x and through a suitable aperture between the heads 8, the latter preferably being split to form two opposed clamp- 10 ing sections.

Slidably mounted upon the barrel is a propelling sleeve 9 having in the mid portion of its length inturned lips 10 adapted to bear against the reduced portion of the barrel 1 and to contact with a spiral spring 11 surrounding the barrel at such reduced portion. The tension of spring 11 tends to move the propelling sleeve 9 forwardly.

Seated between the bars 8x, Fig. 6, are opposed 20 wedges 12 preferably held together by any suitable arrangement such as the semi-circular clip 13. Wedges 12 are of less length than the length of the slot provided between the spaced bars 8x, head 8 and plug 7, so that the wedges are free to 25 move a certain distance longitudinally of the pencil.

In the operation of the device, the parts will normally lie in the position of Fig. 5, in which position the frusto-conical front end of the propelling sleeve 9 acts as a cam device upon the split head 8 to frictionally hold the lead in position inasmuch as the rear section of the split head acts in conjunction with the frusto-conical or flaring formation of the propelling sleeve front 35 end to have wedge action and frictional pressure upon the lead. In such position, the wedges 12 may be idle.

When the knurled section 9x of the propelling sleeve and the sleeve move backward against the 40 tension of spring 11, the propelling sleeve at its cross section of narrowest diameter will gradually engage the wedges 12 and move them backwardly to the position shown in Fig. 12, the lead remaining in position inasmuch as the action upon the 45 wedges merely overcomes the inertia of their weight.

When, however, propelling sleeve 9 is moved backward a distance still greater, the wedges being held against longitudinal movement by abut- 50 ment with plug 7, the wedges will be given a movement toward each other until the lead is firmly engaged and then the lead will resist further movement of the wedges so that the backward thrust upon the propelling sleeve will cause the 55

latter to clampingly engage the wedges. Thus when the propelling sleeve is moved forward, the clamping action on the wedges will be greater than the slight inertia of the lead and the lead 5 will be moved forwardly until the wedges reach the position shown in Fig. 5 and abut split head 8. At such moment, the frusto-conical front end of the propelling sleeve will have reached approximately its maximum clamping position relatively 10 to the tapered rear section of the split head 8 and the lead will be firmly gripped by the latter in the final forward movement of the propelling sleeve. In such final movement, the sleeve moves forward relatively to the wedges and the latter 15 are released from the lead.

In Figs. 13 to 18 inclusive, I have shown a modification of my device in several particulars. In the first place, the propelling sleeve shown at 20 9a is split at its front end to have a spring-like clamping action upon the split head 8a. In such case the normal diameter of the opening at the front end of the propelling sleeve will be less than the diameter of the head 8a and the latter may be of uniform diameter, bevelled toward the 25 lead. Also, to restrict forward movement of the propelling sleeve 9a, the latter is formed with a depressed inwardly extending ring at 14 so that the ends of the wedges 12a will act as stops by contact with ring 14 when the latter is moved 30 beyond its normal forward position. In other respects the pencil elements are the same as that of the preceding figures.

In the structure of Figs. 13 to 18 inclusive, removal of the lead 3a will enable bodily inward 35 movement of the wedges to permit assembly and disassembly of the propelling sleeve 9a.

In the action of the modified device, movement of the propelling sleeve rearwardly to the position of Fig. 15 will cause the split ends of the propelling sleeve to meet the unbroken ring-like 40 section 8aa of the head 8a, thus relieving the lead of clamping pressure. Still further rearward movement of the propelling sleeve will cause the same to grip the wedges 12a in the 45 manner described with reference to the preceding Figures 1 to 12 inclusive, and forward movement of the propelling sleeve will cause the wedges to advance with the lead until the split end of the propelling sleeve passes over upon the split 50 section of head 8a and again clamps the lead. Prior to this, the wedges will have reached the end of their forward movement and will be released from the lead preliminary to succeeding rearward movement of the propelling sleeve to 55 further advance the lead.

It will be seen that the wedges carry the lead forward through the movements of the propelling sleeve, and the sleeve may extend only part of the length of the pencil, making it unnecessary 60 to provide attachments at the rear end of the pencil, as, for example, plungers, for moving the sleeve to its various positions.

It will also be noted that the bell-shaped end of the propelling sleeve is so formed that any line drawn longitudinally of its inner surface is straight and in conformation with a corresponding line extending longitudinally of the surface of the split head 8 with which the bell-shaped end of the sleeve contacts. Thus, the propelling sleeve not only presses the parts of the split head 65 together, but also retains a frictional grip on them, which grips the whole in clamping position until the sleeve is retracted.

In the modification shown in Figs. 13 to 18 inclusive, the propelling sleeve may be of fairly heavy and springy metal, at least at the split end section thereof, where it engages with the clamping head 8a. The inner walls of member 5 8 abutting the lead may be slightly toothed, threaded or roughened so as to enable firm grip upon the lead and corresponding formation may be given to the split head 8a.

It will further be seen that the assembly of 10 the elements is so simple that the moving parts are held together by the insertion of the lead and released for disassembly by removing the lead.

In the device of Figs. 1 to 12 inclusive, insertion 15 of the lead expands split head 8 to such position that it is greater in diameter than the propelling sleeve at its minimum diameter. When the lead is removed, contraction of the split head is permitted and the sleeve may be removed, the 20 wedges, spring, plug and tube 2 disassembled or assembled, as the case may be.

Having described my invention, what I claim and desire to secure by Letters Patent, is as follows:—

1. A mechanical pencil comprising a barrel having a lead passageway extending therethrough, a clamping head at one end of the barrel, through which the lead passes, the head having a frusto-conical rear section, a propelling sleeve mounted upon the barrel for endwise reciprocation the sleeve being formed with a flared end section conforming with the frusto-conical section of the clamping head and with a contiguous reversely tapered section merging 30 into a cylindrical portion telescoped over the main body of the barrel, and a plurality of wedges within the sleeve and between the lead passageway of the barrel and said head, the wedges being bodily movable toward and from the frusto-conical section of the clamping head, and at the 35 end of their movement away from said head being adapted to contact with an abutment carried by the barrel.

2. A mechanical pencil comprising a barrel 40 formed with a longitudinal aperture for the passage of a lead, a split head projected forwardly of the barrel and through which the lead passes, a wedge disposed rearwardly of the split head and having endwise movement limited by a wall 50 of the head and the front wall of the barrel, and a sleeve movable upon the barrel and directly enclosing the wedge, the sleeve having an intermediate restricted section merging into reverse-flared sections, one flared section being adapted 55 to exert a compressive action upon the split head when the sleeve is moved forwardly, and the other tapered section being adapted to exert a compressive force upon the wedge and through the wedge upon the lead when the sleeve is moved rearwardly to such position that an end of the wedge contacts with the said end of the barrel.

3. A mechanical pencil constructed in accordance with claim 2, in which the head is formed intermediate thereof with a relatively unyielding ring section and the propelling sleeve is formed with a split spring end, the sleeve when moved rearwardly bringing the spring end over upon said unyielding ring section of the barrel head. 70

EDWARD J. NEARY.
